INVENTOR,
THOMAS TAAFFE
BY *Horace Barnes*,
ATTORNEY.

UNITED STATES PATENT OFFICE

2,286,588

ILLUMINATED SIGN

Thomas Taaffe, Los Angeles, Calif., assignor of
one-half to Hal R. Blair; Rosalie Taaffe execu-
trix of said Thomas Taaffe, deceased

Application March 13, 1939, Serial No. 261,565

6 Claims. (Cl. 40—130)

This invention relates to improvements in illuminated signs.

The object of my invention is to provide an advertising sign of the class set forth producing a brilliant and scintillant background attractive to the sight and upon which the sign proper is shown and relieved in strong and striking contrast.

A further object of the invention is the provision of a translucent refraction-plate forming the ground against which the sign is displayed and formed with a multiplicity of closely arranged lens elements of relatively small diameters, together with a reflector-sheet mounted to the rear thereof in adjacent parallel relation and formed over its entire surface with angularly arranged facets adapted to intercept and reflect the light cast thereupon to penetrate said refraction-plate to appear to the observer as a myriad of brilliant points of light.

Still further objects of the invention relate to simple and practicable means for moving the reflector-sheet intermittently to animate the light seen through the refraction-plate and cause the same to sparkle, and to novel means for illuminating the sign.

Other objects and advantages residing in my invention, and objects relating to various details and arrangements of parts thereof, will be readily apparent in the course of the detailed description to follow.

The accompanying drawing illustrates by way of example representative forms of my invention, in which:

Figure 1 is a perspective view of an illuminated sign embodying my invention employing luminous gas-filled tubes.

Fig. 2 is a view in rear elevation of the sign with the rear cover-plate removed showing the operative mechanism employed with a sign illuminated by said tubes.

Fig. 3 is a fragmentary perspective view of a modified form of the reflector-sheet together with the solenoid-armature attached thereto.

Fig. 4 is a fragmentary plan view of said reflector-sheet, drawn upon an enlarged scale.

Fig. 5 is a view in cross section taken on line 5—5 of Fig. 2.

Fig. 6 is a view in front elevation of a modified form of the sign.

Fig. 7 is a view in rear elevation, partly broken away, of the sign illustrated in Fig. 6, and with the rear cover-plate removed.

Referring to said views, wherein similar parts are designated by similar reference characters

in the several views, the reference numeral 10 indicates the bottom wall of the sign-casing supported upon short rubber feet 11, and having end walls 12, 12, top wall 13, and front wall 14 enclosing a chamber 15. Said casing may be of parallelepiped form or may have its front vertical corners 16 rounded, as shown, for more attractive design. The rear wall of the casing is open excepting for turned edges 17 of the adjoining walls and is closed by a removable cover-plate 18 secured by screws 20, as seen in Fig. 5.

The front wall 14 of the casing is provided with an opening 19 of oblong configuration having its major axis extending horizontally or longitudinally of the casing and which is closed by a glass plate 21 secured against the front wall by clips 22 at top and bottom. Said plate is formed upon one, preferably its outer, side with an all-over pattern of spherical integrally molded lenses 23 adapted to refract the light issuing therethrough from within the casing or from outside sources.

Within the casing immediately to the rear of the refraction-plate and spaced in relatively close proximity thereto a sheet-metal reflector-sheet 25 is suspended in parallel relation. Said reflector has a highly polished outer surface formed with an all-over pattern of pyramidal nodes 26 indented from the back of the sheet. Thus each node bears three or four light light-directing facets 27 upon its sides to receive and divert the light received thereon upon the refraction-plate in innumerable rays. The reflective surface of the sheet may be coated with an aniline dye of a desired tint to reflect a correspondingly colored light upon the plate 21 in contrast to the color of the exterior sign-characters, as will be understood hereinafter.

Flat springs 28 are fixedly secured at their upper ends to brackets 29 attached to the top wall 13 and extend vertically downward in parallel where at their lower ends they are secured to clips 30 extending from the respective ends of the sheet 25. Said springs are disposed with their flat sides facing the ends of the casing 40 whereby the sheet may swing freely in its parallel relation to the plate 21 when set in motion.

To actuate the reflector-sheet I have provided a solenoid magnet of which the armature 31 is secured to the sheet 25, see Fig. 3, and is directed centrally of a magnetic-coil 32 which may be intermittently energized by any suitable make and break circuit-controlling device. I have shown an electric-lamp socket 33 receiving current through a cable 35 and in which a flasher device 36 of well-known construction is mounted. Elec-

tric circuit wires 37 and 38 extend from the flasher to said solenoid to energize the coil and attract the armature 31 intermittently and thus give the reflector-sheet a continuous series of intermittent impulses that maintain it in motion.

The illumination of the sign may be accomplished from external sources, such as is shown in Fig. 1, wherein a neon gas-filled tube 40 is bent to form sign-letters 41 in a well-known manner and disposed symmetrically in spaced relation before the refraction-plate 21. In such form the light emitted from the glowing tube will be transmitted through the plate 21 upon the reflector-sheet and reflected back to illuminate the plate with a lively, changing and sparkling effect largely caused by the light-refraction effected in both transmissions through the lenses 23 as well as through the breaking up of the light rays by the facets 27 and the motion of the reflector.

In Fig. 6 I have shown sign-letters 42 applied or painted in opaque colors upon the outer surface of the glass-plate 21. The remainder of the plate is translucent and is brilliantly illuminated from a source of light located within the casing. It will of course be understood that the sign-letters may be formed on the refraction-plate by painting the ground around them in opaque colors to form the letters in outline in clear glass. The light source may be of any suitable type that will direct the light both upon the refraction-plate 21 and upon the reflector-sheet 25m such as a neon-tube 43 extending in a parallelogram about the outer margin of the reflector-sheet and between said sheet and the plate 21 so that its light will fall upon both.

Another form of illumination is shown in Fig. 7 wherein an incandescent lamp 45 of the elongated show-case type is mounted in a socket 46 and extends longitudinally of the casing at top or bottom of the reflector-sheet or both and thus sheds its light upon both reflector and refraction-plate.

In the use of neon gas tubes external transformers may be utilized to step up the voltage necessary in their operation in excess of that received over the usual city lighting circuits, or, as shown, the transformer 47 may be included within the casing and receive its current from the socket 33 through wires 48, while the higher-voltage current is conveyed to and from the tubes 40 and 43 over circuit wires 50.

In Fig. 3 I have shown a modified form of the reflector-sheet 25 having parallel corrugations of rounded form 51 extending vertically of the sheet and serving to reflect the light rays cast thereon in various directions and in sweeping lines or waves across the refraction-plate 21 thus causing the light observed through the plate to sparkle as heretofore described.

It will be apparent that an extremely brilliant and attractive sign may be produced by following out either plan of construction described, the variance therebetween being mainly in the source of light desired. Such eye attracting effects are largely produced through the provision of the reflector-sheet whose broken surface in close and moving juxtaposition to the refraction-plate 21 redirects substantially all light rays impinging thereon forwardly upon said plate to strongly illuminate the same whether such light originates from the external sign-tubes 40 or from internal light sources, such as the neon tubes 43 or lamps 45, both of which are arranged to cast the major

portion of their light rays upon the reflector-sheet.

Having described my invention, what I claim is:

5. 1. An illuminated sign, consisting of a casing, a translucent plate in the front wall of said casing having one side thereof formed with light refracting elements, a reflector-sheet suspended for vibratory movements in parallel relation and 10 in near proximity to said plate and formed with light-reflecting facets over its outer surface, means to actuate said sheet, and a luminous gas-filled tube formed in sign-characters positioned externally of said plate and arranged to 15 cast light rays through said plate and upon said sheet.
2. An illuminated sign, consisting of a casing, a translucent plate in the front wall of said casing having one surface comprised of light-refracting elements and having opaque portions delineating 20 sign characters, a reflector-sheet suspended in close parallel relation to said plate and formed with its proximate surface in light-reflecting facets, a light-source disposed to cast light rays upon said sheet and upon said plate, and means to 25 actuate said sheet in non-rotary vibratory motion.
3. An illuminated sign, consisting of a casing, a refraction-plate mounted in a wall of said casing formed with a multiplicity of integral lens 30 elements over one of its surfaces, a reflector-sheet suspended for vibratory motion in parallel relation to said plate within the casing and formed over its forward surface with a multiplicity of nodes having light-reflecting facets upon their sides, and means to illuminate said plate and said sheet.
4. A sign of the character described having: a forward refraction-plate forming a multiplicity of elements to refract light transmitted through the plate; a movable reflector sheet spaced to the rear of said refraction-plate, said sheet having an uneven light-reflecting surface; and means to vibrate said reflector sheet laterally at an amplitude and frequency to cause the light-transmitting area of said refraction-plate to appear as a sparkling myriad of brilliant lights.
5. A sign of the character described having: a forward refraction-plate forming a multiplicity of elements to refract light transmitted through the plate; a movable reflector sheet spaced to the rear of said refraction-plate, said sheet having an uneven light-reflecting surface; means to continually move said reflector sheet in a vibratory manner relative to said plate; illuminating means positioned intermediate the planes of said plate and sheet; and means masking forwardly radiating light from said illuminating means to prevent unreflected light from passing directly forward from said illuminating means through said refraction-plate.
6. A sign of the character described having: a forward wall, a portion of said wall being light transmissive and a surrounding portion of said wall being opaque; a plurality of refraction elements distributed over said light transmissive portion of said wall; a movable reflector sheet spaced to the rear of said light transmissive portion of the wall, said sheet having an uneven light-reflecting surface; means to continually move said reflector sheet in a vibratory manner relative to said wall; and illuminating means positioned intermediate said sheet and said wall directly behind said opaque portion of the wall.

THOMAS TAAFFE.
